UNITED STATES PATENT OFFICE.

MELVIN SOLOMON GROH, OF TORONTO, ONTARIO, CANADA, ASSIGNOR, BY MESNE ASSIGNMENTS, TO THE GENERAL FIREPROOFING COMPANY, OF YOUNGSTOWN, OHIO, A CORPORATION OF OHIO.

MACHINE FOR EXPANDING SLITTED SHEETS.

Application filed November 27, 1923. Serial No. 677,262.

To all whom it may concern:

Be it known that I, MELVIN SOLOMON GROH, a subject of the King of Great Britain, and a resident of the city of Toronto, in the county of York, in the Province of Ontario, Canada, have invented certain new and useful Improvements in Machines for Expanding Slitted Sheets, of which the following is the specification.

10 My invention relates to improvements in machines for expanding slitted corrugated sheets for producing expanded metal and the object of the invention is to devise means whereby the expanding of the slitted corrugated sheet can be done for the full length and width of the sheet.

15 A further object is to devise means for simultaneously engaging corresponding slitted portions of the corrugations.

20 A still further object is to devise means for holding the forward edge of the slitted corrugated sheet in engagement with the expanding means.

25 Another object is to devise means for holding the unexpanded portion of the slitted corrugated sheet in a plane substantially at right angles to the portion expanded by the expanding means.

30 My invention consists of a machine constructed and arranged all as hereinafter more particularly described and illustrated in the accompanying drawing in which:

Fig. 1 shows a side elevation of the machine.

35 Fig. 2 is a plan view thereof broken away intermediately.

40 Fig. 3 is an enlarged elevational detail of a portion of the roll and table showing the slitted corrugated sheet inserted therebetween.

45 Fig. 4 is a fragmentary horizontal cross section through the line 4—4 Figure 1, and

Fig. 5 is a plan view of a portion of the slitted corrugated sheet showing the disposition of the staggered slits, one part being unexpanded and the other expanded.

Like characters of reference indicate corresponding parts in the different views.

50 1 is a base provided with the vertically extending column 2 having the vertical slot 3 in its rear face of dove-tailed cross section, into which is inserted the correspondingly dove-tailed tongue 4 of the vertically

disposed leg 5 of the table support 6. 7 is an internally threaded boss on the leg 5 and 8 is an aligned internally threaded boss on the base. 9 is a threaded spindle having its upper and lower end respectively threaded into the bosses 7 and 8, said spindle being provided with a hand wheel 10 which is secured thereto, the threads of the upper portion of the spindle 9 being in opposed relation to the threads on the lower portion.

11 is the table for carrying the slitted corrugated sheet, said table having the depending skirt 12 at its forward end, said table being provided with longitudinally disposed countersunk slots 13 therein through which freely extend the headed screws 14, said screws being threaded into the table support 6. 15 is a transverse rib provided at the rear end of the table support 6 through which is threaded the setscrews 16, the forward ends of which engage the rear edge of the table 11.

17 is a roll supporting frame extending upwardly from the base 1 and provided with the arms 18 into which is journalled the shaft 19 of the roll 20, the periphery of said roll being provided with a plurality of continuous longitudinally extending die ribs of sawtooth cross section and coextensive in length with the roll body, as is clearly illustrated in Figures 1 and 3 of the drawing. 21 are upwardly extending spaced apart brackets formed on the frame 17, said brackets being connected together by a cross member 22 of L-shaped cross section, said member 22 being provided with a plurality of vertically extending slots 23 through which extend the setscrews 24 which are threaded into the vertically extending tensioning or drag plate 25, the lower end 26 of which is bevelled and disposed above the leaving or expanding edge of the slitted blank carrying table 11. 27 are a plurality of setscrews threaded through the horizontal portion of the member 22 and adapted to engage the top of the plate 25.

100 The ribs 28 on the roll preferably do not extend around the entire circumference, a space constituting a land 29 being provided as illustrated in Figure 1.

105 The shaft 19 of the roll is provided with a drive pulley 30 connected by any suitable

means to a line shaft or other source of power.

The slotted corrugated sheet used in forming the expanded metal has the corrugations disposed transversely and the slits longitudinally. The slits are interrupted slits, each alternate row being staggered in relation to the intermediate rows.

The operation of my machine is as follows:

The slotted corrugated sheet is applied to the table 11 and the plate 25 so adjusted that it exerts a certain amount of tension on the sheet, the forward edge of the sheet up to 15 the first row of slits protruding over the forward edge of the table. The roll is then positioned so that the land 29 is opposite the table. Upon the rotation of the roll in a clockwise direction the substantially continuous shoulder of the first rib 28 will engage at one operation the forward edge of the sheet throughout its entire length, pulling it down as is illustrated in Figure 3. Each successive rib likewise engages the succeeding longitudinal row of strands constituting the next protruding portion of the sheet, pulling it down in a similar manner. The length of the roll 20 is substantially equal to 20 the length of the sheet of slotted corrugated material, and the circumference of the roll is substantially equal to the width of the finished expanded sheet.

The vertical and horizontal adjustments for the table 11 are for the purpose of taking different sizes of stock.

From the above description it will be apparent that I have devised a simple and effective means of expanding a slotted corrugated sheet which will function simultaneously across the entire width thereof and which will, moreover, be positive in its feed.

What I claim as my invention is:

1. A machine for expanding slotted metal sheets comprising a supporting table for an unopened slotted sheet, and a rotated roll having upon its periphery a circumferential series of spaced die-ribs coextensive in length with the roll body and each presenting a substantially continuous shoulder adapted to engage at one operation a single row of strands throughout the entire length of the sheet, and the successive die ribs on the roll periphery being arranged to engage and pull successive rows of strands of the sheet lying between the rows of slits in a direction at right angles to the unopened and unexpanded part of the sheet as the roll is rotated.

2. A machine for expanding slotted corrugated sheets comprising a rotated roll having longitudinal ribs, a sheet supporting table, adjustable means for engaging the sheet in the vicinity of its forward edge, the successive ribs on the roll engaging and pulling out the successive portions of the sheet

lying between the rows of slits in a direction substantially at right angles to the unexpanded part of the sheet as the roll is rotated, and adjustable means for varying the distance between the forward edge of the 70 table and the periphery of the roll.

3. A machine for expanding slotted corrugated sheets comprising a frame, a roll rotatably supported in the frame and having a plurality of longitudinal ribs, a supporting 75 table located at one side of the roll, means for vertically adjusting said table support, a corrugated sheet carrying table arranged in said table support, means for horizontally adjusting said table, and means positioned above the leaving edge of said table for engaging and tensioning the edge of the slotted corrugated sheet.

4. A machine for expanding slotted corrugated sheets comprising a frame, a roll rotatably supported in the frame and having a plurality of longitudinal ribs, a supporting table located at one side of the roll, means for vertically adjusting said table support, a corrugated sheet carrying table 80 arranged in said table support, means for horizontally adjusting said table, brackets carried by the frame which supports the roll, a plate carrying member extending between 85 said brackets, and vertically extending corrugated sheet engaging plates adjustably carried by said plate carrying member.

5. A machine for expanding slotted corrugated sheets comprising a rotatable roll having a plurality of longitudinally extending 90 ribs, a vertically and horizontally adjustable support for the slotted corrugated sheet arranged at one side of the roll, and means disposed above the leaving edge of said support for engaging with the corrugated sheet 95 and constituting a drag thereon.

6. A machine for expanding slotted corrugated sheets comprising a rotatable roll having a plurality of longitudinally extending 100 ribs, a vertically and horizontally adjustable support for the slotted corrugated sheet arranged at one side of the roll, and a drag plate disposed above the leaving edge of said support and having the lower edge thereof 105 beveled, and means for vertically and horizontally adjusting said plate with reference 110 to the leaving edge of said support.

7. A machine for expanding slotted corrugated sheets comprising a base having an upright frame and upright column members, a roll having a plurality of longitudinal ribs rotatably journaled in the frame members, a corrugated sheet supporting device mounted to be vertically adjustable on 115 said column members, said device comprising a sheet carrying table having a horizontal portion and a vertical depending apron portion and furnishing an expanding edge between the two, means for adjusting the horizontal portion of said table, and means 120

positioned above the expanding edge of said table for engaging with a corrugated sheet disposed on the table.

8. A machine for expanding slitted corrugated sheets comprising a rotatable roll having a plurality of longitudinal ribs regularly spaced on its periphery except for a predetermined space thereby providing a longitudinally extending land on the roll, means

for supporting the slitted corrugated sheets 10 so that the same will be passed to the successive ribs on the roll thereby to expand the slitted sheet into meshes, and means cooperating with the support for constituting a drag on the slitted unexpanded portion of 15 the sheet.

MELVIN SOLOMON GROH.
